UNITED STATES PATENT OFFICE.

SPENCER C. CARY, OF BROOKLYN, NEW YORK.

DESIGN FOR A PAIL-HOOK.

SPECIFICATION forming part of Design No. 27,908, dated November 30, 1897.

Application filed September 27, 1897. Serial No. 653,267. Term of patent 14 years.

To all whom it may concern:

Be it known that I, SPENCER C. CARY, a citizen of the United States of America, and a resident of Brooklyn, Kings county, New York, have invented a new and useful Improvement in a Design for Pail-Hooks, of which the following is a specification, reference being had to the accompanying drawings, forming part of the same, in which—

10 Figure 1 is an upper face view of a pail-hook, exhibiting my new design; and Fig. 2 is a side or edge view of the same.

The design consists in a pail-hook having prongs at the ends, which are connected one to the other by an intermediate two-stranded body portion, and the essential features of the design are prongs or tangs and an intermediate two-stranded body portion, the outlines of one strand being convexly-curved

lines continuous with the lines defining the 20 prongs and constituting or extending to the outer lines of the face of the article, and the outlines of the other strand being reversely-convexed curved lines contacting at their ends with the inner of the side lines of the 25 first strand, substantially as shown.

What I claim as my invention, and desire to secure by Letters Patent, is—

The design for a pail-hook, substantially as shown and described.

In testimony that I claim the foregoing as my invention I have signed my name, in presence of two witnesses, this 22d day of September, 1897.

SPENCER C. CARY.

Witnesses:

PETER B. VERMILYA,
